UNITED STATES PATENT OFFICE.

ZERAH G. HAYDEN, OF ELDORA, IOWA

COMBINED SCISSORS AND SQUARE.

1,296,660.

Specification of Letters Patent. Patented Mar. 11, 1919

Application filed March 15, 1918. Serial No. 222,621.

To all whom it may concern:

Be it known that I, ZERAH G. HAYDEN, a citizen of the United States, residing at Eldora, in the county of Hardin and State of Iowa, have invented certain new and useful Improvements in Combined Scissors and Squares; and I do hereby declare the following to be a full, clear, and exact description of the invention, such as will enable others skilled in the art to which it appertains to make and use the same.

This invention relates to improvements in scissors, shears, snippers and the like, and the primary object of the invention is to provide an improved pair of scissors and the like so formed that the same can be readily used as compasses, a square, try-square, and rule.

Another object of the invention is the provision of a pair of scissors and the like having the edges of the blades thereof graduated, and adjustable means to limit the opening movement of the blades in relation to each other, so that the same can be set at any desired angle to each other so that the scissors can be used as a square or try-square, the angle of the blades in relation to each other being readily shown by a scale carried by one of the blades.

A further object of the invention is the provision of a pair of scissors or the like having the edges of the blades thereof graduated, a hollow rivet pivotally securing the blades together, the blades having a plurality of registering apertures spaced at equidistant points therein, the hollow rivet being arranged to receive a pointed instrument to engage the work to be marked, and form a pivot, and the registering apertures in the blades being arranged to receive a scribe or marking point for scribing arcs, circles and the like.

A still further object of the invention is the provision of a pair of scissors or the like having an auxiliary blade pivoted thereto, for various purposes, as will be readily apparent as the description of the application proceeds.

A still further object of the invention is to provide an improved device of the above character which is durable and efficient in use, one that is simple and easy to manufacture, and one that can be placed upon the market at a reasonable cost.

With these and other objects in view the

invention consists in the novel construction, arrangement and formation of parts, as will be hereinafter more specifically described, claimed, and illustrated in the accompanying drawing, forming a part thereof, in which:

Figure 1 is a plan view of the improved scissors showing the blades in open position and being adapted to be used as a square;

Fig. 2 is an edge elevation of the improved tool;

Fig. 3 is a transverse section taken through the pivot on the line 3-3 of Fig. 2 showing the pointed instrument inserted through the hollow rivet to form a pivot for the scissors, when the same is to be used as compasses; and

Fig. 4 is a transverse section taken on the line 4-4 of Fig. 2 showing the marking point in position in the registering apertures, when the same is to be used as compasses.

Referring to the drawing in detail, where-in similar reference numerals designate corresponding parts throughout the several views, the numeral 1 generally indicates the improved tool, including a pair of blades 2 and 3 pivoted together by means of a hollow rivet 4 having its ends upset as at 5 to firmly clamp the same in position. Each blade is provided with an operating handle 6 and one handle is suitably shaped for receiving the thumb of the operator and the other handle is suitably shaped for receiving the fingers of the operator. One of the handles is provided with the ordinary shoulder stop 7 for limiting the closing movement of the blades in relation to each other and an outward extension 8 is formed on the same and the outer edge of the extension 9 lies parallel with the cutting edge of one of the blades. The blades 2 and 3 are provided with inner cutting edges 9. Both edges of the blades are provided with suitable graduations 10, so that the blades can be readily used as a rule when so desired.

The extension 8 is provided with a longitudinally extending threaded bore 11, which receives an adjustable thumb-screw 12 having its upper end knurled as at 13 to provide a hand grip. The lower end of the screw is adapted to engage the opposite blade 2 to limit the opening movement thereof, for a purpose which will hereinafter more fully appear. The blade 3 is provided adjacent

to the extension 8 and limiting shoulder 7 with suitable graduations 14 forming a protractor 45 for showing the different angles in a circle, and the blade 2 is adapted to be set to the desired angle and the set-screw 11 is then turned so as to bring the same into engagement with the blade and the handles 6 of the blades are so operated so as to hold the blades against the set-screw 10 and the markings are made from either edge of the blades 2 and 3. Thus the same can be readily used as a square or try-square. The blades 2 and 3 are provided with apertures 15 at equidistantly spaced points, 15 which are adapted to register with each other, when the blades are in their closed position; and when it is desired to use the tool as compasses, a suitable pointed instrument 16 is inserted in the hollow rivet 20 4 and the pointed end of the same is stuck in the work on which the arc or circle is to be inscribed, and a suitable marking instrument 17 is placed in the desired registering apertures 15 and the blades are turned 25 on the point 16 as a pivot and the marking point is held against the paper and the arc or circle inscribed.

The upper surface of the blade 2 adjacent to the pivot 4 is provided with a recessed portion 18 in which is fitted a knife blade 19 and the same is held in position by a suitable pivot pin 20. A leaf spring 21 is secured to the bottom wall of the recess and engages the pivoted end of the blade 19 and holds the same in its closed or open position. The pivoted end of the blade is provided with angularly related shoulders 22 for engaging the free end of the leaf spring

so that the same can readily hold the same in its open and closed position.

From the foregoing description it can be seen that an improved tool is provided which can be readily used as scissors, and also as compasses, a square, or try-square, and rule.

In practice, I have found that the form of my invention, illustrated in the accompanying drawing and referred to in the above description as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention as set forth.

What I claim as new is:—

In a pair of scissors including a pair of pivoted blades, operating handles therefor, a protractor formed on one blade adjacent the rear end thereof, the opposite blade being adapted to coöperate with the protractor for determining the angular relation of the blades to each other, and a set-screw carried by one blade for engagement with the opposite blade to limit the opening movement of the blades in relation to each other, as and for the purpose specified.

In testimony whereof I affix my signature in presence of two witnesses.

ZERAH G. HAYDEN.
